(57) **CLAIM**

The ornamental design for support cushion for computers and terminal devices, as shown and described.

DESCRIPTION

FIG. 1 is a rear left perspective view of the support cushion for computers and terminal devices showing my design;

FIG. 2 is a right elevational view thereof;

FIG. 3 is a left elevational view thereof;

FIG. 4 is a rear elevational view thereof;

FIG. 5 is a top plan view thereof; and,

FIG. 6 is a bottom plan view thereof.

The texture markings shown in portions of the claimed design surfaces indicate a texture that is present throughout the claimed design surfaces.
